MICROSCOPE

John George Shield, St. Leonards-on-Sea, England, assignor to The Educational Supply Association Limited, Stevenage, Hertfordshire, England

Filed July 2, 1971, Ser. No. 159,580

Claims priority, application Great Britain Jan. 5, 1971

Term of patent 14 years

Int. Cl. D16—06

U.S. Cl. D57—1 E

FIG.1.

FIG.2.

FIG.3.

FIG.4.

FIG.5.

FIG.6.

4

4

FIG.7.

FIG.8.

FIG. 1 is a front elevation of a microscope showing my new design;

FIG. 2 is a side elevation thereof;

FIG. 3 is a rear elevation thereof;

FIG. 4 is a section taken on line 4—4 of FIG. 6;

FIG. 5 is a bottom plan view;

FIG. 6 is a top plan view thereof;

FIG. 7 is a front perspective view as seen from the left of FIG. 1; and

FIG. 8 is a rear perspective view as seen from the right of FIG. 2.

The features of my design sought to be patented reside in the shape and configuration of the microscope.

I claim:

The ornamental design for a microscope, as shown and described.
